[57] ABSTRACT

A gas cushion vehicle provided with one or more lift fan duct sealing valves for maintaining gas cushion pressure in the event of lift fan stoppage wherein a sealing valve comprises a flexible valve membrane arranged across the cushion end of the or each gas duct leading from the or each lift fan to the cushion, the membrane being flexibly movable into an open position clear of the end of the duct when the lift fan is operating and movable into a closed position so as to close the end of the or each duct when the or each lift fan associated with the or each duct is not operating and the gas pressure acting within the cushion is higher than the gas pressure acting within the or each duct.

4 Claims, 1 Drawing Figure

GAS CUSHION VEHICLES

The present invention relates to a gas cushion vehicle and more particularly to a non-return valve in a gas cushion vehicle arranged so as to prevent gas contained within the cushion from escaping by reverse flow through the lift fans in the event of a lift fan stoppage.

In U.S. Pat. No. 3,425,505 (equivalent to U.K. application No. 18,564/65) there is described a gas cushion vehicle provided with flaps movable to close off the ducts between the lift fans and the gas cushion so as to prevent gas reversing up the ducts in the event of lift fan failure. Such flaps were controlled by a complicated mechanical and hydraulic arrangement which was expensive to provide and being complicated required careful maintenance.

It is usual for the gas to be pressurised by one or more lift fans and supplied through a duct or ducts to the or each cushion. If the lift fan or one of the lift fans fails it is desirable to prevent the loss of gas from said cushion or cushions by reverse flow through the inoperative lift fan.

In an attempt to simplify the arrangement for closing off the ducts there was designed and installed in one of our vehicles a valve comprising one or more invertible segments of flexible material. This arrangement is described in my U.K. Pat. No. 1,300,751 (equivalent to U.S. application No. 228,774, filed Feb. 23, 1972, now U.S. Pat. No. 3,841,433). When the segment inverted there was a tendency for the points of attachment of the segment to the valve frame to wear. Also the valve itself was large and the valve casing cumbersome resulting in some loss of efficiency in the lift system.

An object of the present invention is therefore to attempt to overcome these disadvantages.

The present invention consists of a gas cushion vehicle having a hull provided with one or more lift fans and a duct from the or each fan to the gas cushion, a non-invertible flexible valve membrane arranged across the cushion end of the or each duct, the membrane being flexibly movable into an open position clear of the end of the duct when the lift fan is operating and movable into a closed position so as to close the end of the or each duct when the or each lift fan associated with the or each duct is not operating and the gas pressure acting within the cushion is higher than the gas pressure acting within the or each duct, whereby on lift fan stoppage the duct is sealed.

The arrangement is such that only one flexible membrane need be provided for each duct or group of ducts; the membrane being non-invertible there is less wear; and because the space required for the membrane to operate is minimal, the membrane also can be fitted in a vehicle having a flexible skirt within the existing space between the end of the duct and the skirt and within the upper part of the flexible skirt. Because the membrane is clear of the end of the duct the flow in the duct is uninterrupted, and the duct resistance kept minimal.

The invention will now be described with reference to a drawing, which shows one embodiment of the invention by way of example, in which drawing the FIGURE shows a diagrammatic cross-section of a cushion

supply duct and flexible skirt with valve membrane in a gas cushion craft according to the invention.

In the drawing can be seen part of the hull 1 of a gas cushion vehicle having a flexible skirt 2. The skirt 2 has an upper part 3 formed of an outer loop 4 and inner loop 5. The skirt 2 has a lower part 6 formed from a main segment 7 and inner segment 8. Within the hull 1 of the vehicle is a lift fan duct 9 having an end 10 which opens into a longitudinal space 11 formed within the upper part 3 of the skirt. Across the duct end 10 is a flexible membrane 12 attached to the outer loop 4 at 13 and to the hull at 14.

When the lift fan (not shown) is operating air is blown down the duct 9 into space 11 forcing the membrane 12 into the position shown by the unbroken line in the drawing. Air is then deflected longitudinally along the space 11 by the membrane and flows down into the main and inner segments 7 and 8 into the gas cushion.

When a lift fan stops, there is a reversal of air flow in the inoperative fan duct, due either to air supply from other fans or to cushion pressure leaking to atmosphere. This flow blows the membrane 12 into the position 15 shown by the broken line, so as to block the fan duct end 10 and seal the duct 9.

I claim:

1. A gas cushion vehicle having a hull provided with lift fan means, duct means leading from the fan means to the gas cushion and having an outlet, a flexible valve membrane having a pair of substantially parallel edges which are attached to the hull on opposite sides of said outlet so that the membrane extends across said outlet, whereby the membrane is flexibly movable into an open position clear of said outlet when the lift fan means is operating and is movable into a closed position so as to close said outlet when the lift fan means is not operating and the gas pressure acting within the cushion is higher than the gas pressure acting within the duct means, and a flexible skirt attached to said hull, with one of said edges of the valve membrane attached to said flexible skirt.

2. A gas cushion vehicle as claimed in claim 1, wherein the other of said edges of the valve membrane is attached directly to the hull of the vehicle.

3. A gas cushion vehicle as claimed in claim 1, wherein said flexible skirt comprises an outer loop and an inner loop, said one of said valve membrane edges being attached to said outer loop of the flexible skirt.

4. A gas cushion vehicle having a hull provided with lift fan means, duct means leading from the fan means to the gas cushion and having an outlet, and a flexible valve membrane having a pair of substantially parallel edges which are attached to the hull on opposite sides of said outlet so that the membrane extends across said outlet, whereby the membrane is flexibly movable into an open position clear of said outlet when the lift fan means is operating and is movable into a closed position so as to close said outlet when the lift fan means is not operating and the gas pressure acting within the cushion is higher than the gas pressure acting within the duct means, one of the edges of said valve membrane being attached directly to said hull.
